UNITED STATES PATENT OFFICE.

CHARLES L. HOPKINS, OF RIVER FOREST, ILLINOIS, ASSIGNOR TO BENJAMIN ELECTRIC MANUFACTURING COMPANY, OF CHICAGO, ILLINOIS, A CORPORATION OF ILLINOIS.

ELECTRIC SWITCH.

Application filed September 19, 1919. Serial No. 324,971.

To all whom it may concern:

Be it known that I, CHARLES L. HOPKINS, a citizen of the United States, residing at River Forest, in the county of Cook and 5 State of Illinois, have invented new and useful Improvements in Electric Switches, of which the following is a full, clear, concise, and exact description, reference being had to the accompanying drawing, forming a 10 part of this specification.

My invention relates to electric switches, and more specifically to pull switch sockets.

One of the objects of my invention is to provide an improved switch in which the 15 circuit is simultaneously broken at two points, thus dividing the arc.

A further object of my invention is to provide an improved switch socket in which the circuit to both of the receptacle contacts 20 is simultaneously broken.

Further objects will appear from the detailed description to follow and from the appended claims.

In the drawings in which two embodiments 25 of my invention are shown,

Fig. 1 is a top plan view of a pull switch socket embodying my invention;

Fig. 2 is a section substantially on the line 2—2 of Fig. 1;

Fig. 3 is a section substantially on the line 3—3 of Fig. 2;

Fig. 4 is a section substantially on the line 4—4 of Fig. 2;

Fig. 5 is a section substantially on the line 35 5—5 of Fig. 1;

Fig. 6 is a section substantially on the line 6—6 of Fig. 2;

Fig. 7 is a detail perspective view of part 40 of the switch frame;

Fig. 8 is a detail perspective view of part of the switch;

Fig. 9 is a detail perspective view of one 45 of the rotary contact members;

Fig. 10 is a plan view of a pull switch socket showing another form of my invention;

Fig. 11 is a section substantially on the line 11—11 of Fig. 10;

Fig. 12 is a section substantially on the 50 line 12—12 of Fig. 11;

Fig. 13 is a section substantially on the line 13—13 of Fig. 11;

Fig. 14 is a section substantially on the line 14—14 of Fig. 11;

Fig. 15 is a detail perspective view of one 55 of the rotary contact members;

Fig. 16 is a detail perspective view of the oscillating operating member;

Fig. 17 is a detail perspective view of one 60 of the spring contact members; and

Fig. 18 is a side elevation of one of the contact carriers.

Referring now to the drawings and first to the form shown in Figs. 1 to 9 inclusive, in order to give a general idea of the 65 construction, it is here stated that:

The pull switch socket here shown comprises a sheet metal casing 20 and insulating base 21, and shell and center contacts 22 and 23 respectively (the shell and center contacts being supported by the insulating base 21, and the insulating base and the contacts supported thereby being housed in a casing 20) and a ratchet pull switch mechanism 24, supported by the insulating base 21, which breaks both sides of the circuit, simultaneously, so that when the switch is in "off" position, both of the receptacle contacts, that is the shell contact 22 and the center contact 23, are "dead". The switch mechanism comprises two spring contact fingers 25 and 26 (the spring contact finger 25 being always electrically connected with the wiring terminal 27, and the spring contact finger 26 being always electrically connected 75 with the wiring terminal 28) and two contact members 29 and 30 which cooperate with the spring contact fingers 25 and 26 respectively the contact members being mounted to rotate about the same axis, in different 80 parallel planes. (the contact 29 being always electrically connected with the shell contact 22, and the contact 30 being always electrically connected with the center contact 23). The contacts 29 and 30, in their 85 movement, move simultaneously out of contact with respect to the contact fingers 25 and 26. From this construction it follows that the circuit from the wiring terminal 27 to the shell contact will be broken at the 90 same time that the circuit from the wiring terminal 28 to the center contact will be broken at the 95 same time.

Referring now to the switch construction in detail, the contacts 29 and 30 are secured 100 on a rotatable contact carrier 31 which is operated by means of an oscillating switch lever 32, through the intermediary of a

ratchet mechanism 33. The contact carrier, and switch lever 32, are mounted in brackets 34 and 35. The bracket 34 is always electrically connected with the rotary contact 29, 5 and with the shell contact, and the bracket 35 is always electrically connected with the other rotary contact 30 and with the center contact 23, these brackets thus serving not only to support the rotary contact carrier 10 and switch lever, but also serving as part of the electrical circuit. The bracket 35 is secured in place on the insulating base 21 by means of a screw 36, which also serves to assist in holding the shell contact 22 in place 15 on the base, and to electrically connect the bracket 34 and shell contact. Similarly the bracket 34 is held in place on the insulating base 21 by means of a screw 37, which also serves to hold the center contact 23 in place 20 on the base and to electrically connect the center contact 23 and the bracket 35.

The rotary contact 29 is held in place on the contact carrier by means of an integral inwardly extending arm 38 (Fig. 9) having 25 a collar portion 39, into which extends a lug or boss 40 on the contact carrier, the collar 39 extending into an opening in the bracket 34, which thus forms a bearing for one end of the contact carrier. The arm 38 not only 30 serves to hold the brush 29 in place on the contact member carrier, but electrically connects the contact portion of the same with the bracket 34. The contact member 30 is held in place on the contact carrier by means 35 of an inwardly extending arm 41, (Fig. 5) which has an opening through which extends a shaft 42 secured to the contact carrier 31. This arm 41 not only serves to hold the contact member 30 in place on the contact carrier but also electrically connects 40 the contact portion of the same with the shaft 42, which also is part of the circuit. This arm 41 is so constructed that it forms one of the ratchet members of the ratchet 45 connections between the switch lever 32 and the contact carrier. For this purpose it is provided with shoulder portions 43 which are engaged by ratchet teeth 44, stuck up from a sheet metal ratchet member 45, which 50 is secured to the switch lever 32 (Fig. 6). This ratchet member 45 is secured to the contact carrier by means of a collar portion 46, formed integral with the ratchet member, and extending through registering 55 openings in two insulating discs 47 and 48, forming part of the switch lever, the collar portion 46 being riveted over, to securely hold the ratchet member in place on these discs, and also to securely hold these discs 60 together. These discs 47 and 48 serve to support an arcuate chain rail 49 (Fig. 4) which supports the chain 50 and to which the chain 50 is secured by means of hook fingers, as indicated at 51. The chain rail 49 is secured to the disc 48 by means of

three lugs 53, which extend through openings in the disc 48 and are riveted over as indicated in Fig. 2. The disc 47 serves to cover up the bent-over ends of these lugs 53 and prevent short circuiting between them 70 and the live parts of the switch. The oscillating movement of the switch lever 32 is limited to substantially 180 degrees, by means of stop lugs 54, formed integral with the discs 47 and 48, which stop lugs engage 75 suitably located shoulders 55 and 56, on the insulating base 21.

For returning the switch lever after it has been operated by the pull chain 50, a coil torsion spring 57 is provided, one end of 80 which is secured in notches in the insulating discs 47 and 48, as indicated at 58 (Figs. 2, 4 and 6) and the other end of which is secured to a combined spring securing and bearing member 59 (Fig. 8) which is adjustably mounted in the bracket 35. This member 59 may be a sheet metal stamping, having a cup-shaped bearing portion 59^a which fits in an opening in the bracket 35, and having a flange portion 60 which positions it with respect to this bracket. This flange portion 60 has a positioning lug 61 stuck up therefrom which can be made to engage in any one of a plurality of notches 62 in the bracket 35 (Fig. 5) to adjustably 90 position the spring securing member in the bracket 35 to adjust the tension of the coil torsion spring 57, which spring 57 is secured to a lug 63 extending from the flange portion 60 of the spring securing member. 100 The cup-shaped portion 59 is provided with a slot 64 for engagement with a screw-driver, whereby the spring securing member may be pushed inwardly to disengage the lug 61 from the notch 72 and turned to adjust the tension of the spring. When the spring securing member is thus adjusted to the desired position, the screw-driver is withdrawn, and the spring 57 will force 110 the spring securing member outwardly, and cause the positioning lug 61 to enter the desired one of the notches 62.

The circuit has been outlined in connection with the description of the parts of the pull socket, and is as follows: From the wiring terminal 28, through the spring contact finger 26, rotating contact 30, arm 41, shaft 42, bracket 35 and screw 37 to the center contact, thence to whatever translating device is inserted into the receptacle to the shell contact 22, and through the screw 36, bracket 34, rotating contact 29 and spring contact finger 25 to the wiring terminal 27. 115

The operation of the device is as follows: 120 Assuming that the switch is in "off" position, as shown, and it is desired to turn it on, the pull chain 50 is pulled down, to move the switch lever 32 and contact carrier 31 through 180 degrees of movement. During 125 this movement of the contact carrier, the

spring contact fingers 25 and 26 ride upon the spiral portions of the contact carrier, and at the end of the movement snap down from the spiral portions, and into contact with the contacts 29 and 30 respectively. This simultaneously electrically connects both of the receptacle contacts 22 and 23 with the wiring terminals 27 and 28 respectively. When the pull chain 50 is released, the torsion spring 57 returns the switch lever 32 to its original position, the contact carrier 31, however, remaining stationary during this return movement of the switch lever. The spring fingers 25 and 26 would prevent any return movement of the contact carrier, by engagement with the shoulders behind which they have just snapped. If it is desired to turn the switch "off," the pull chain 50 is again pulled down, to move the switch lever and contact carrier through 180 degrees of movement. During this movement of the contact carrier, the contact fingers 25 and 26 ride upon the contact portions contacts 29 and 30 and at the end of the movement snap down from these contacts into engagement with the carrier, thus breaking the circuit on both sides of the receptacle. When the pull chain 50 is released, the spring 57 again returns the switch lever, the contact carrier, however, remaining stationary during this return movement. The spring contact fingers 25 and 26 would resist any return movement of the contact carrier, by engagement with the shoulders back of which they have just snapped.

In the form of my invention shown in Figs. 10 to 19 inclusive, the casing 20, the insulating base 21, the shell and center contacts 22 and 23, may be the same as in the form just described. The principal differences between the two constructions shown are in the switch mechanism itself. In the form just described the switch lever and pull chain are located to one side of the contact carrier and its contacts. In the form about to be described, the switch lever and pull chain are mounted to operate between the two rotatably mounted contacts. In both forms, however, the circuit is simultaneously broken on both sides of the receptacle. In this form, the switch mechanism comprises two rotatably mounted contact carriers 65 and 66, the contact 65 being always electrically connected with the shell contact 22, and the contact 66 being always electrically connected with the center contact 23, and a pair of spring contact fingers 67 and 68 for cooperation with the contacts 65 and 66 respectively, the contact 67 being always electrically connected with the wiring terminal 69, the contact 68 being always electrically connected with the wiring terminal 70. In this form of my invention the two spring contact fingers 67 and 68 may be identical,

and may be formed of sheet metal stampings. The contacts 65 and 66 are similar in construction, one being the reverse of the other, that is, one might be termed "right hand" and the other "left hand," and the contact carriers 71 and 72 are also similar in construction, being right and left hand. These contact carriers 71 and 72 are connected together by means of a rod 73, this rod being fluted, as indicated in Figs. 11 and 12 to prevent relative rotation between the carriers and the shaft. The contact 65 is held in place on the carrier 71 by means of an inwardly extending arm 74, formed integral with the contact, and having a collar 75, (Fig. 15) into which extends an integral boss 76 on the carrier 71. This collar 75 extends into an opening on a bracket 77, the bracket 77 thus forming a bearing for the carrier. This arm 74 not only serves to hold the contact in place on the carrier, but serves as part of the electrical connection, in that it electrically connects the contact portion of the contact member with the bracket 77, which in turn is electrically connected with the shell contact 22 by means of a screw 78, which also serves to hold the threaded shell contact 22 and the bracket 77 in place on the insulating base 21.

In a similar manner, the contact 66 is held in place on the carrier 72 by means of an inwardly extending arm 79 (Fig. 14) having a collar 80 into which extends an integral boss 81 of the carrier 72. The collar 80 extends into an opening in the bracket 82, whereby the bracket 82 forms a bearing for the carrier 73. The arm 79 serves not only to hold the contact in place on the carrier, but also serves to electrically connect the contact portion of this member with the bracket 82, which is part of the circuit, in that the contact is electrically connected to the center contact 23 by means of a screw 83, which screw also serves to hold the center contact 23 and the bracket 82 in place on the insulating base 21. By reason of the construction just described, the contact 65 is always electrically connected with the shell contact, and the contact 66 is always electrically connected with the center contact.

The contact carriers are operated by means of a switch lever 84 (Fig. 16) which may be a sheet metal stamping, having an opening 85 therein to receive an integral boss 86 on the carrier 72 and having ratchet teeth 87 for engagement with corresponding ratchet recesses 88 formed in the side face of the carrier 72. The switch lever has a chain rail portion 89 for supporting the pull chain 90, which is secured to the switch lever by means of two hook portions 91 formed integral with the switch lever. For returning the switch lever after it has been operated by the pull chain 90, a coil torsion spring 92 is provided, which surrounds the

bosses 86 and 93 of the carriers, and has one end 94 secured in a recess in the insulating base 21, and its other end secured to the switch lever as indicated at 95.

- 5 The circuit arrangement of this form of my invention is substantially the same as in the form previously described. When the switch is closed the circuit is from the wiring terminal 70 to the spring contact finger 10 68, contact 66, bracket 82, screw 83 to the center contact, thence to whatever translating device is inserted in the receptacle, to the shell contact 22, and through the screw 78, bracket 77, contact 65, and spring contact 15 finger 67 to the wiring terminal 69.

If the switch is in "off" position as shown in the drawing, and it is desired to turn the switch "on" the pull chain 90 is pulled down, to move the contact carrier 180 degrees. The 20 movement of the switch lever is limited to substantially 180 degrees by an extension 96 on the switch lever, which engages an abutment 97 on the insulating base 21, in one direction, and the movement of the lever is 25 limited in the other direction by the engagement of the hook 91 with another abutment portion 98 of the insulating base.

During this movement of the contact carrier, the spring contact fingers 67 and 68 ride 30 upon the spiral portions of the contact carriers, and at the end of this movement snap down into engagement with the contacts 65 and 66, respectively, thus completing the circuit to both sides of the receptacle simultaneously. When the pull chain 90 is released, the spring 92 returns the switch lever to its original position. During this return movement of the switch lever, the contact carriers remain stationary. If it is now desired to 40 turn the switch "off" the pull chain is again pulled down, causing the carriers to move 180 degrees. During this movement the spring contact fingers 67 and 68 ride upon the contacts 65 and 66 respectively, and at 45 the end of the movement snap off from the ends of these contacts and into engagement with the brush carriers, thus quickly and simultaneously breaking the circuit on both sides of the receptacle. When the pull chain

is released, it is again returned by means of 50 a spring 92.

Having thus described my invention, what I claim as new and desire to secure by Letters Patent is:

1. A switch mechanism comprising an insulating contact carrier constructed in two separable mating parts, each having a portion of reduced diameter and a portion of greater diameter, the portions of reduced diameter facing each other; a torsion spring 55 surrounding said reduced portions; a driving member supported upon said reduced portions; a flexible operating member winding on said driving member; a curved contact arranged on the larger portion of each 60 of said mating parts; each of said parts having a flange extending beyond its contact to form a barrier between the same and the driving and flexible operating members; conducting bearings for said contact carrier 65 electrically connected to said curved contacts; and stationary contacts engaging said curved contacts and arranged to snap off the same simultaneously.

2. A switch mechanism comprising a rotatable insulating contact carrier constructed in two separable parts, a curved contact carried by each part, each of said curved contacts having a length of substantially 180 degrees, a pair of conducting bearings each 70 connected electrically with one of said curved contacts, ratchet and pawl operating means 75 for driving said contact carrier, said operating means comprising an oscillating member confined between the parts of said carrier 80 and removable therefrom only when the parts are separated, a coiled spring also confined between said parts for returning said oscillating member and arranged to yieldingly hold the ratchet and pawl members in 85 engagement with each other, means for operating said oscillating member, and stationary contacts engaging said curved contacts and arranged to snap off the same simultaneously.

In witness whereof, I have hereunto subscribed my name.

CHARLES L. HOPKINS.
